CONSISTENCY REGULATOR

Carl G. Muench, Chicago, Ill., assignor to The Celotex Corporation, Chicago, Ill., a corporation of Delaware

Application September 25, 1952, Serial No. 311,462

2 Claims. (Cl. 137—91)

This invention relates to a new and novel consistency regulator, particularly for use in regulating or maintaining a uniform consistency of an asbestos fiber or similar stock. The device hereof, while it might be used for a wood fiber stock or other forms of fiber stock, is, however, particularly for use in connection with what might be termed a "heavy" stock; that is, one wherein the fiber, which is in suspension, is of a specific gravity higher than that of the woods ordinarily used for producing paper fiber. The use of the device, however, is not necessarily limited to use with a fiber stock since it will likewise serve as consistency regulator for a dispersion or suspension, in particular where the material dispersed or suspended is a heavy material, that is, of a density of about that of or exceeding the density of water. Regulation of the consistency of relatively high consistency stocks is best accomplished by the device hereof; that is, it operates more satisfactorily in regulating the consistency of a stock, say, of 10% consistency compared to, say, a 1% consistency, which condition, however, is only relative, that is, the operation or degree of regulation is more satisfactory with stocks of higher consistencies.

Ordinarily, consistency regulators for paper fiber stocks are in general quite unsatisfactory for use with stocks in which are suspended materials of a density higher than the usual woods used for paper fiber, and likewise with respect to stocks of consistencies higher than those usually used in connection with the manufacture of paper products; that is, stocks running at the most to about 2% consistency.

The principle involved in this regulator is that of maintaining, in the line of flow of the stock to the forming machine, a continuously uniform volume of stock which can be continuously weighed so that as the weight of such volume of stock varies, correction is made to maintain such volume of stock at a uniform weight. Such uniform volume of stock is maintained in the line but out of physical connection therewith by providing a suitable tank to which the stock is supplied but without physical connection to the supplying conduit or the like, and from which the stock flows without physical connection between the tank and the conduit or like to which the tank discharges. The stock continuously flows into and out of the tank, discharge being into the tank at one end and from the tank at the other end over a lip or weir, so that at all times there is substantially a uniform volume of stock in the tank. The tank is preferably somewhat elongated, that is rectangular in shape and of U-shape cross section, so that a slow speed cylindrical agitator may be revolved in the tank to maintain a uniform suspension therein. The tank may be set on the platform of a scale, or in any other suitable manner connected, so that it is supported by the scale and will be continuously weighed, and suitable controls are positioned with respect to the weight indicator so that above or below the optimum weight, indicating high consistency or low consistency, respectively, the appropriate control device will be actu-

2

ated to increase make-up water to dilute the stock to the desired consistency range or, on the other hand, to decrease the supply of make-up water to bring the consistency up to within the desired range.

5 The preferred construction of the consistency regulator hereof and its operation will be described in detail below in connection with the drawings illustrative thereof, and wherein—

Figure 1 is a side elevation, part being broken away;

Figure 2 is a top plan view;

Figure 3 is an end elevation;

Figure 4 is an elevation of the other end of the device;

Figure 5 is a cross-section taken on line 5—5 of Figure 1; and

Figure 6 is a cross section taken on line 6—6 of Figure 1.

10 The consistency regulator hereof comprises a tank 10 which preferably is rectangular in shape and at least twice as long as it is wide, or in any case relatively narrow in comparison with length. This tank 10 is preferably of U-shape cross section for a purpose which will be fully evident in connection with the following description of the device. It is to be understood that this tank 10 need not necessarily be of the construction as just described, but that such may assume various forms so long as the objective thereof is achieved. Any form of tank member may be utilized so long as it is designed to maintain a constant volume of the stock in the tank, which stock may be freely discharged into the tank from a supply conduit or the like and freely discharged from the tank to a conduit or the like in which provision is incorporated for maintaining a uniform dispersion or suspension of the stock therein.

15 The tank 10 as illustrated is provided mounted to its respective end walls with bearings 11, in which bearings 11 there is mounted a shaft 12. Mounted on shaft 12 there is provided a cylindrical paddle agitator, the paddles being designated by numerals 13. The specific construction of the agitator is not of importance, and as the details of the construction are clearly evident from the drawings, it is believed sufficient to mention that such cylindrical agitator includes arms 14 and clamping members 15 which, respectively, support the paddles 13 and serve to clamp the cylindrical agitator to shaft 12. The

20 cross section of the tank being U-shape, as above referred to, it is readily apparent that the cylindrical agitator, in its rotation, will keep the stock in the tank well agitated to maintain the desired uniformity of suspension or dispersion of the stock therein.

25 The cylindrical agitator is preferably revolved relatively slowly at the rate of, say, 20, 40 or 60 R. P. M. by any suitable driving means which, in the case of the construction illustrated, constitutes an electric motor as the prime driver with suitable speed reduction provided between the motor and the shaft 12. A motor with an integrated speed reducer, identified in the drawings by numeral 20, through gears 21 and 22 drives shaft 12 through a coupling 23. It is to be understood, of course, that any other type of drive may be used and that the only requisite is that it be a drive which will rotate the agitator at slow speed.

30 It is to be particularly noted that tank 10 is what might be termed a "free member," that is, it is not physically connected to the conduit discharging into the tank nor is it physically connected to the conduit to which it discharges. The conduit 25, discharging to the tank, it will be seen terminates above the level of the stock in the tank and discharges to the tank at one end with the stock falling through gravity from the lower end of the conduit. At the opposite end of the tank the discharge is over a lip 26 from which the discharged stock falls by

gravity into a discharging tank which is entirely separate from the consistency regulating tank 10. The consistency regulating tank with its agitator and drive are mounted on a base 27 which rests on and is supported on the platform 28 of a scale.

From the foregoing it should be fully evident that when the consistency regulator is in operation, since tank 10 and its associated drive base and the like are at all times supported only on the platform of the scale, the scale will at all times indicate the then instantaneous weight of such assemblage together with the weight of the constant volume of stock contained in the tank, and as the weight of such volume of stock may vary due to variation of consistency, that the scale arm lever or indicator will so evidence. The scale indicating device may be suitably integrated with control mechanisms for adjusting the consistency of the stock in the tank 10 to maintain the weight of the stock in the tank within predetermined limits denoting the desired consistency.

The balance arm of the scale is designated as 31, carrying a pointer or contact member 32 which may be connected to one side of an electrical circuit as by means of wire 33. Contacts are mounted to a support member such as 34, the contacts being designated by numerals 35 and 36 and to which contact members there are connected wires 37 and 38 extending to a suitable electric valve control mechanism 39, which serves to adjust the valve or control 40 in water line or conduit 41. It is to be understood, of course, that the water line control valve may be operated by hand or by any one of the numerous valve control devices which are available on the market. Since the construction and controls for such valve control device vary with the various such devices, no attempt has been made in the drawings to do more than diagrammatically indicate a such device with conventional controls whereby, as the pointer 32 contacts one or the other of the contact members 35 or 36, a circuit is closed which causes the valve control mechanism to operate, to open or close the valve as required. The required type of valve control device is one which opens or closes the valve by a small increment and then cuts out, for an adjustable inactive period, whereupon the control is reactivated and contact of pointer 32 with a contact 35 or 36 will again cause actuation of the valve by a small increment. The specific features of the valve control device are not of the essence nor a part of the invention hereof.

At the far end of tank 10, or the end provided with discharge 26 but separate from tank 10, there is provided a discharge tank 44 which is suitably supported and provided with a constant level overflow with intake pipe 45 which discharges to conduit 46 any overflowing stock back into the system in any appropriate manner. This discharge tank 44 is also provided with valve or gated distributing outlets 47 controlled by gates 48 which can be raised and lowered by means of suitably connected adjusting mechanisms operated by means of hand wheels 50. In the illustration there is shown three distributing outlets 47, each provided with a gate 48 through which distributing outlets stock is supplied to separate conduits 51 which lead to the various cylinder chests of board-forming machine.

In accordance with the foregoing it should be readily apparent that the construction described comprises a relatively simple apparatus for maintaining stock fed to a board-forming machine at a uniform consistency, that is, at a consistency between certain predetermined, relatively narrow limits. To accomplish this desired result, stock of relatively high consistency is fed, as by conduit 25, for discharge into tank 10 of the consistency regulating apparatus. Water is supplied to the stock in stock conduit 25 by means of water line or conduit 41, in which there is provided a valve 40. Assume a stock suspension is being delivered to tank 10 at a substantially constant rate and diluted from its original consistency to substantially

the desired consistency by water supplied through water line or conduit 41. If the consistency of the stock in tank 10 is above or below the optimum, the scale pointer 32 will move up or down appropriately and complete a circuit through one or the other of contacts 35 and 36 to

appropriately operate valve control mechanism 39 to supply less water or more water to the high consistency stock as may be required to bring up the consistency of the stock or to lower the consistency of the stock in tank 10.

In the foregoing it will be seen that there is provided a relatively simple apparatus for maintaining stock consistency in tank 10 between the limits of a predetermined plus or minus tolerance so that the dilute stock discharged from tank 10 to be supplied to the board machine is at

what can be referred to as of uniform consistency. It is believed to be clearly evident that the stock in tank 10 will be maintained at a uniform depth, since the discharge is over a discharge 26, and that this stock will be kept in constant and uniform agitation by the rotation

of the agitating structure including paddles 13. Finally, it is believed fully evident that the stock of uniform consistency discharged from tank 10 to separate discharge tank 44 will, through distributing outlets 47 and stock conduits 51, supply stock of uniform consistency to the cylinder chests of the board machine being supplied by

the consistency regulator.

While nothing particularly has above been said concerning stock consistencies or the like, the device hereof is well adapted for the regulation or control of the con-

sistency of asbestos and cement suspension supplied as stock to an asbestos-cement board machine. In such case, the asbestos and cement are ordinarily put into suspen-

sion in a beater, usually at a consistency of somewhere between 25 and 30%, and which would then be stock

of high consistency supplied to the consistency regulator hereof. Since a consistency of about 15% may be the optimum for the stock supplied to the cylinder chest of an asbestos-cement board machine, the contacts 35 and 36 would be adjusted so as to control the amount of

diluting water supplied through water line or conduit 25 to maintain the consistency of the stock as discharged from the consistency regulator between the limits of 14 and 16%, and to thus supply stock to the cylinder chest at an average consistency of 15%.

The construction and operation of the consistency regulator having been above described in detail, I claim:

1. A consistency regulating apparatus comprising in combination a fluid receiving tank, an agitator mounted in the tank and connected means operating the agitator, a stock supply conduit terminating at its end out of contact with but discharging over the tank, a separate secondary tank adjacent the receiving tank, the receiving tank provided with a discharge weir, the discharge weir having its outer end positioned over but out of contact with the secondary tank, a water pipe discharging over the receiving tank, a flow control device mounted in the water line and having associated operating means, a base on which are mounted the fluid receiving tank and agitator operating means, a scale on which such base is mounted, the scale provided with a weight-indicating arm and means associated with the weight-indicating arm and activated by the such arm and controlling operation of the water line flow control device operating means.

2. A consistency regulating apparatus comprising in combination a fluid receiving tank, an agitator mounted in the tank and connected means operating the agitator, a stock supply conduit terminating at its end out of contact with but discharging over the tank, a separate secondary tank adjacent the receiving tank, the receiving tank provided with a discharge weir, the discharge weir having its outer end positioned over but out of contact with the secondary tank, a water pipe discharging over the receiving tank, a flow control device mounted in the water line and having associated operating means, a base on which are mounted the fluid receiving tank and agi-

tator operating means, a scale on which such base is mounted, the scale provided with a weight-indicating arm and means associated with the weight-indicating arm and activated by the such arm and controlling operation of the water line flow control device operating means, and in the separate secondary tank to which the discharge weir delivers, a fixed overflow conduit to limit the maximum head of fluid therein and in a wall of said tank, gated ports providing controlled feed from said tank.
